CLAIM

The ornamental design for a shoulder temperature and compression therapy device, as shown and described.

DESCRIPTION

FIG. 1 is a top perspective view of a shoulder temperature and compression therapy device, according to an embodiment;

FIG. 2 is a front view of the shoulder temperature and compression therapy device, according to an embodiment;

FIG. 3 is a rear view of the shoulder temperature and compression therapy device, according to an embodiment;

FIG. 4 is a right side view of the shoulder temperature and compression therapy device, according an embodiment;

FIG. 5 is a left side view of the shoulder temperature and compression therapy device, according to an embodiment;

FIG. 6 is a top view of the shoulder temperature and compression therapy device, according to an embodiment; and,

FIG. 7 is a bottom view of the shoulder temperature and compression therapy device, according to an embodiment. The broken lines showing portions of the shoulder temperature and compression therapy device form no part of the claim.
